(No Model.)

S. M. VAUCLAIN.
COMPOUND ENGINE.

No. 431,860.

Patented July 8, 1890.

UNITED STATES PATENT OFFICE.

SAMUEL M. VAUCLAIN, OF PHILADELPHIA, PENNSYLVANIA.

COMPOUND ENGINE.

SPECIFICATION forming part of Letters Patent No. 431,860, dated July 8, 1890.

Application filed February 8, 1890. Serial No. 339,721. (No model.)

To all whom it may concern:

Be it known that I, SAMUEL M. VAUCLAIN, a citizen of the United States, and a resident of Philadelphia, Pennsylvania, have invented 5 certain Improvements in Compound Engines, of which the following is a specification.

The object of my invention is to provide in a compound engine or locomotive a device which will to a certain extent equalize the 10 strain on the connecting devices of the high and low pressure piston-rods when starting a train, and at the same time secure the desired extra power for starting heavy trains or loads. This object I attain in the following manner, 15 reference being had to the accompanying drawings, in which—

Figure 1 is a side view of a locomotive-cylinder casting, showing my improvement. Fig. 2 is a sectional view of the cylinders of a compound engine, showing my improvement. 20 Fig. 3 is an end view of the cylinder shown in Fig. 2. Fig. 4 is a sectional view of the cylinders, the piston-rods of which are connected to cranks diametrically opposite each 25 other; and Fig. 5 is a sectional view of the valve.

I will describe my invention as applied to the cylinder of a compound locomotive; but it will be understood that my invention can 30 be applied to a stationary or marine engine as well.

A is the high-pressure cylinder, B the low-pressure cylinder, and D the valve for controlling the inlet and exhaust of steam into 35 and from the high and low pressure cylinders.

a is the piston of the high-pressure cylinder, and b the piston of the low-pressure cylinder.

In the arrangement shown in Figs. 1, 2, and 40 3 the piston-rods of the high and low pressure cylinders are connected together by a cross-head, the pistons working together. The inlet and exhaust ports of the high-pressure cylinder are shown at c c', and the inlet and exhaust ports of the low-pressure cylinder at d d', the several ports connecting with the valve-chamber, and the valve D controlling the admission of steam thereto and the exhaust of steam therefrom.

50 E is a passage connecting both ends of the high-pressure cylinder, consisting, in the present instance, of an ordinary pipe E', tapped

into the cylinder, as shown, and provided at each end with a suitable valve e e—in the present instance in the form of a plug-valve; but 55 it will be understood that any form of valve may be used in carrying out my invention, and in place of the two valves shown in Figs. 1 and 2 a single valve may be used, as shown in Fig. 4, and instead of using the pipe E' to 60 connect the two ends of the cylinder a passage may be formed in the casting of the cylinder, as shown in said Fig. 4. A lever e' on each plug-valve is connected to a rod F, an extension F' of which passes to the cab of the 65 engine, and is under the control of the engineer, so that the valve can be opened or closed by the simple longitudinal movement of the rod.

Two valves are employed at each end of the 70 passage E instead of the central valve, to prevent the loss of steam at each exhaust, which would be contained in the pipe if a single valve was used; but I do not restrict myself to this construction, as a single valve in some 75 cases may be found preferable.

The action of the steam is as follows: If, for instance, steam is admitted in front of the high-pressure piston, the valves e e are opened and communication established with both 80 ends of the cylinder through the passage E. The steam wire-draws through the passage into the rear end of the high-pressure cylinder, thence through the exhaust-passage to the valve D, and is admitted to the forward 85 end of the low-pressure cylinder through the inlet-passage d. Thus the first movement of the engine is what may be termed a "compound" movement. When the engine has started well, the valves or cocks e e are closed. 90 The engine then works on the compound principle in the usual manner.

By the above-described mechanism, therefore, I am enabled to more readily start a train on a grade or a train that is heavily 95 loaded than heretofore, owing to the fact that the compound action takes place immediately on the first stroke of the engine, at the same time equalizing the strain to a certain extent on both the high and low pressure pistons.

In Fig. 4 the piston-rods of the high and low pressure cylinders are not connected together by a cross-head; but each are connected to a crank, one being opposite the other,

so that in this case the steam in the rear of the high-pressure cylinder would pass to the rear of the low-pressure cylinder.

I claim as my invention—

- 5 1. The combination, in a compound engine, of the high and low pressure cylinders, a passage forming a communication between the front and the rear of the high-pressure cylinder with a valve controlling the flow of steam through said passage from one end of the cylinder to the other, substantially as described.
- 10 2. The combination, in a high and low pressure cylinder, a valve or valves therefor, a passage communicating with each end of the high-pressure cylinder with two valves, one at each end of the passage, said valves being under the control of the engineer, and adapted to allow or cut off the flow of steam
- 15

through the passage from one end of the cylinder to the other, substantially as described. 20

3. The combination, of the high and low pressure cylinder, valve or valves therefor, a pipe E', forming a passage E between the ends of the high-pressure cylinder, plug-valves e e, having arms e', with a connecting-rod F attached to both arms, and having an extension passing to the cab of the locomotive, substantially as described. 25

In testimony whereof I have signed my name to this specification in the presence of 30 two subscribing witnesses.

SAMUEL M. VAUCLAIN.
